(57) **CLAIM**

The ornamental design for a smart pill box as shown and described.

DESCRIPTION

FIG. 1 is a perspective view of a smart pill box showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken line portions of the smart pill box in FIGS. 1–6 represent unclaimed portions of the claimed design and form no part thereof. The oblique shade lines in the drawings represent a transparent surface.

1 Claim, 6 Drawing Sheets(56)
